ELECTRIC CIRCUIT BREAKER

George Dewar, Stretford, Manchester, England,
assignor to General Electric Company, a corporation of New York

Application August 24, 1937, Serial No. 160,691
In Great Britain September 15, 1936

7 Claims. (Cl. 200—153)

This invention relates to electric circuit breakers of the kind having trippable means by which the circuit breaker is maintained closed, and by which the circuit breaker is immediately tripped and the circuit opened again in case the breaker is closed on a short circuit. The trippable means is usually of the kind providing what is commonly termed a trip-free mechanism, namely a mechanism arranged so as to be trippable at any time in the closing operation of the circuit breaker. It has been found that the contacts may be damaged by arcing if the closure is not completed within a certain time after the contacts touch, or, in other words, if during the final closing action the circuit breaker fails to close the contacts at a predetermined speed. Thus, when the moving contact initially engages the co-operating contact said moving contact may hesitate or even be reversed in its movement, due to the electromagnetic forces set up at said contacts. Devices have therefore been proposed by which backward movement of the moving contact, or lag of the moving contact, during the closing movement, will cause the tripping mechanism to operate and the circuit breaker immediately to open. The object of the present invention is the provision of an improved mechanism of this kind which shall be simple and certain in its operation.

According to the invention the operating lever or handle of the circuit breaker, which may be suitably operated by electric means or manually during closure of the breaker, is connected to an actuating lever through trip-free mechanism and is further connected with energy-storing means, such as a fly-wheel, which is thereby caused to rotate during the operation of closing in such a manner that if the speed of movement of the operating lever is reduced relatively to that of the actuating lever the continued rotation of the fly-wheel, due to its inertia, will release the trip-free mechanism so as to permit the circuit breaker to open.

In carrying out the invention the operating lever may be connected with the flywheel through a link and rack-and-pinion movement and the continued movement of the rack-bar under the rotation of the flywheel when the speed of movement of the operating lever is reduced a predetermined amount relative to its initial movement causes a movement of the link relative to the operating lever, which movement releases the trip-free mechanism.

The trip-free mechanism may comprise any suitable arrangement such as a trip lever, pivoted to the operating lever for detachably inter-

connecting the operating lever and the actuating lever, and a link between the operating lever and the rack-bar for actuating the trip lever so as to disengage the actuating lever in response to relative movement between said operating lever and link, thus releasing the trip-free mechanism.

In order that the invention may be clearly understood it will now be described with reference to the accompanying drawing, the single figure of which is an elevational view showing by way of example one form of circuit breaker constructed according to the invention.

The circuit breaker shown is of the conventional double-break type having a bridge 1 carrying the movable contacts connected to a lever 2 pivoted on a fixed axis 3. The movable breaker element or lever 2 is connected through a link 4 with an actuating lever 5 pivoted at a fixed point 6 coaxially with an operating element such as a lever 7 which, as shown, is provided with a handle for manual operation. The free arm of the actuating lever 5 has a catch 8 with which engages under normal conditions a roller 9 carried by a trip lever 10 pivoted at 11 to the operating lever 7. Also pivoted to the operating lever 7 coaxially with the trip lever 10 is a link 12 to the end of which a rack-bar 13 is connected. The link 12 has a projection 14 for a purpose hereinafter described. At 15 is movable energy-storing means such as a flywheel connected through 16 a "cushion" drive to a shaft 17 by a spring 18 or other cushioning connection and carrying a pinion 19. The shaft 16 rotates in fixed bearings and the rack-bar 13 is guided in engagement with the pinion 19 by the roller 18 which rotates on a pivot supported in a fixed bracket 20. The operating lever has a projection 21 adapted to engage with the link 12 as shown. The circuit breaker, the fixed contacts of which are shown at 22, is contained in a tank 23 which is filled with liquid 24 to a suitable level.

The operation of the device is as follows: The drawing shows the circuit breaker in the open position. The roller 9 of the trip lever in this position is in engagement with the catch 8 of the actuating lever 5 and if the operating lever 7 is moved downwards to the position shown at 7' in broken lines the actuating lever 5 will be rotated in the clockwise direction and through the link 4 will rotate the lever 2 in the clockwise direction to the position indicated in broken lines 2', thus raising the bridge piece 1 to its upper position in which its contacts engage with the fixed contacts 22. During this movement the stop 21 carried on the operating lever 7 engaging with the

- link 12 forces the rack-bar 13 downwards so that the flywheel 15 is caused to rotate in the clockwise direction. If during this movement the motion of the operating lever is checked or reduced 5 in speed sufficiently in excess of the normal deceleration consequent upon the meeting and final closure of the circuit breaker contacts the flywheel 15 due to its inertia will continue to maintain its speed of rotation and will move the rack-bar 13 downwards relatively to the operating handle 7. This will cause rotation of the link 12 on its pivot to such an extent that the projection 14 will engage with the trip lever 10 and rotate the same clockwise about its pivot so as to release 10 the roller 9 from the catch 8 on the actuating lever 5. Accordingly the lever 5 is free to rotate on its pivot in the counter-clockwise direction independently of lever 7 thereby permitting the 15 circuit breaker to open in the usual way.
- 20 A trip coil 24 may be provided acting on a plunger 25 which can operate a pivoted trip lever 26 to cause it to engage with the trip arm 10 when the operating lever 7 is in its lowest or near its lowest position so as to cause the roller 25 9 to release the actuating lever 5 and open the circuit breaker when required and provide trip-free operation. Other forms of electromagnetically or manually operated tripping apparatus obviously may be employed with the circuit breaker operating mechanism shown.

I claim:—

1. Electric circuit breaker operating mechanism comprising a movable circuit breaker element, an operating element and trip-free structure interconnecting said elements including a tripping device, energy-storing means movable in accordance with the circuit-closing movement of said operating element at a speed corresponding to that of said element, and means operatively relating said energy-storing means to said tripping device for causing actuation thereof in response to predetermined reduction in the closing speed of said operating element.
2. Electric circuit breaker operating mechanism comprising a movable breaker element, an operating element, and trip-free structure including a tripping device interconnecting said elements, and means having appreciable mass related to said operating element so as to move at a speed corresponding to that of said operating element during the normal circuit-closing operation, said means also coacting with said tripping device so that the inertia of said mass is effective to actuate said tripping device in response to predetermined reduction in the closing speed of said operating element.
3. Electric circuit breaker operating mechanism comprising a movable breaker element, an operating element, a trip-free linkage interconnecting said elements including a latch for holding said linkage in thrust-transmitting position, a rotatable member having appreciable mass, and means interconnecting said operating element and rotatable member for causing rotation thereof at a speed corresponding to the circuit-closing speed of said element, said interconnecting means being also operatively related to said latch for causing tripping thereof, the inertia of said

tating mass in response to predetermined reduction in the closing speed of said operating element causing actuation of said latch.

4. Electric circuit breaker operating mechanism comprising a movable breaker element, an operating element, trip-free linkage interconnecting said elements, a latch for holding said linkage in thrust-transmitting position, a fly-wheel operatively connected to said operating element so as to be rotated at a speed corresponding to the circuit closing speed of said element, and means responsive to the inertia of said rotating fly-wheel for actuating said latch to the tripping position in response to predetermined reduction in the closing speed of said operating element.

5. Electric circuit breaker operating mechanism, comprising a movable breaker element, an operating element, trip-free structure including a latch interconnecting said elements, a rotatable member having appreciable mass and means including a rack and pinion device for interconnecting said operating element and rotatable member for rotating said member at a speed corresponding to the circuit-closing speed of said element, and means relating said rack and pinion connection to said latch for causing tripping thereof due to the inertia effect of said rotating member when the speed of said operating element is retarded a predetermined extent.

6. Electric circuit breaker operating mechanism comprising a movable breaker element, an operating element, trip-free structure including a latch interconnecting said elements, a fly-wheel having a resilient connection with the operating shaft thereof, means including a rack and pinion for interconnecting said shaft to said operating element, said rack being related to said latch so that predetermined movement thereof causes tripping of said latch, said operating element causing rotation of said fly-wheel through said rack and pinion at a speed corresponding to the circuit-closing speed of said element and the inertia of said fly-wheel causing relative movement of said rack with respect to said element to cause tripping of said latch in response to predetermined reduction in the closing speed of said operating element.

7. Electric circuit breaker operating mechanism comprising a movable breaker element, a pivoted operating element, trip-free linkage interconnecting said elements, a latch pivotally mounted on said operating element for holding said linkage in thrust-transmitting position, a rotating member having an appreciable mass, a gear rack pivotally connected at one end to said operating lever and at its other end through a coacting pinion to said rotating member, said operating element causing rotation of said member at a speed corresponding to the circuit-closing speed of said element through said rack and pinion, and means interrelating said rack and latch whereby the inertia of said rotatable member causes relative movement of said rack in the reverse direction upon predetermined retardation of said operating element to cause tripping of said latch.

GEORGE DEWAR.
